UNITED STATES PATENT OFFICE.

STEPHEN JENCICK, OF MINNEAPOLIS, MINNESOTA.

DOUBLE-ACTING MOTOR.

1,324,353.

Specification of Letters Patent.

Patented Dec. 9, 1919.

Application filed August 9, 1915. Serial No. 44,555.

To all whom it may concern:

Be it known that I, STEPHEN JENCICK, a subject of the State of Austria, residing at the city of Minneapolis, in the county of 5 Hennepin and State of Minnesota, have invented a new and useful Double-Acting Motor, of which the following is a specification.

My invention relates to improvements in internal combustion engines wherein the 10 ton of each cylinder receives an impulse upon each alternate downward, and upon each alternate upward traverse of the cylinder thereby greatly reducing the weight of the motor and the number of parts used 15 therein as compared with motors now in common use. A particular object of my invention is to provide cooling means for the double acting piston thereby rendering the foregoing construction practical.

20 I attain these objects by the mechanism illustrated in the accompanying drawings, in which,

Figure 1 is a sectional side view of my motor. Fig. 2 is a front view of the double 25 acting piston and piston rods employed therewith in the motor, Fig. 3 is a side view of the double acting piston and piston rods employed in the motor. Fig. 4 is a cross 30 sectional view of the stationary cross-head and piston rods on the line A A in Fig. 1.

Similar figures refer to similar parts throughout the several views.

The lower half 1 of the crank case, and 35 upper half 2 of the crank case, which also serves as the base of the motor, carbureter 3 and carbureter manifold 4, are similar to corresponding parts in the other motors now in use, and therefore need not be described in detail.

40 Cylinder 5 is jacketed by the ordinary type of water jacket 6, of which port 7 is the outlet. Within cylinder 5 are located two distinct chambers separated by stationary cross-head 8 to wit, an upper explosion chamber 5^a and a lower pump chamber 5^b. In the pump chamber is located pump piston 9, mounted upon connecting rod 11 by wrist pin 10 and connected to crankshaft 12 in the usual manner.

45 Hollow piston 13 travels in the upper or explosion chamber of cylinder 5 and is provided with hollow piston rods 14, which are formed integrally with the piston.

Cross-head 8 is held firmly in position by 50 sleeve 14' which is held to the cylinder 5

by screws 15, which thereby clamp the cross-head 8 between the end of sleeve 14 and the shoulder formed in cylinder 5 adjacent to the top of cross-head 8, where the diameter of the upper portion of the cylinder is reduced below that of the lower portion. 60

Spark plugs 16 and 17 are suitably positioned in the upper and lower ends of the combustion chamber respectively. Cam shaft 18 is driven from pump shaft 19 by 65 the sprockets and chain indicated in dotted lines in Fig. 1. Pump shaft 19 is driven from crank shaft 12 by the sprockets and chain indicated in dotted lines in Fig. 1.

Pump 20 is mounted upon shaft 19 and is 70 adapted to circulate the liquid cooling medium through tube 21, water jacket 6, outlet 7 and other suitable cooling means in connection therewith. Exhaust valves 23 and 22 open into exhaust manifolds 24 and 75 25 respectively. The valves 23 and 22 are actuated by rocker arms 26 and 27 pivoted at their extremities 28 and 29. These rocker arms engage the valves and are actuated by the cam 30, which is driven in 80 proper timed relation with respect to the crank shaft.

The exhaust valves and their operating mechanism just described are duplicated in structure and arrangement and serve as the 85 inlet valves which communicate with the intake manifold 4. They are arranged to the rear of the exhaust valves, as shown in Fig. 1, and serve to establish communication at the proper time between the intake manifold and the combustion chambers. 90

Dust cover 31 provides a suitable covering and protection for the valve mechanism and serves to decrease the amount of noise given off from the action of the valve mechanism. 95

Oil reservoir 32 attached to the bottom of the crank case is provided with means 33 for cooling the contents of the reservoir.

Force feed lubricating pump 34 is adapted to force oil under pressure through tubes 100 35, 36, 37 and 38 to all parts of the motor requiring lubrication. Tube 38 has its outlet on the inside of sleeve 14 and produces a continuous flow of oil into the space within the sleeve. As pump piston 9 travels below 105 the outlet of tube 38 it collects oil and after it passes said outlet upon its upward movement it forces the oil collected above the piston into one of the hollow piston rods 14 at ports 39 through said rod, piston 13, the 110

other rod 14 and out through port 40 from whence it drips over the wrist pin, connecting rod and crank shaft into the base of the motor and from thence it drains to reservoir 32.

- Fig. 4 shows the construction of cross-head about the piston rods which is adapted to prevent leakage of any gas from the lower combustion chamber through the cross-head. Contracting ring 41 located in an annular internal groove of the cylinder 5, is suitably held in place and adapted to contact about, and remain in close contact with the outer surfaces of piston rods 14. Expanding ring 42 located in an annular external groove of the cross-head 8, is suitably held in place and adapted to expand against and remain in close contact with the inner surfaces of piston rods 14. Spring wedges 43 are adapted to wedge between piston rods 14 and part of cross-head 8 thereby holding the surface of the wedges adjacent to the sides of piston rods 14 in close contact therewith. Heretofore double acting motors have not been provided with suitable cooling means for the double acting pistons and the piston rods which pass through one of the combustion chambers have been inadequately cooled and very much exposed to the heat of the explosions in such combustion chambers. The construction employed in my patent provides a positive cooling circulation through the double acting piston with few additional parts and without additional moving parts.

I claim:

1. In a motor of the kind described a cylinder, two combustion chambers in said cylinder separated one from the other by a hollow double acting piston, two hollow piston rods connected to the double acting piston and formed to correspond with and fit against the sides of the interior of the cylinder, and means for providing a circulation of the liquid lubricating medium of the motor through said piston rods and piston.
2. In a motor of the kind described a cylinder, two combustion chambers in said cylinder separated one from the other by a hollow double acting piston, two hollow piston rods connected to the double acting piston and formed to correspond with and fit against the sides of the interior of the cylinder, a stationary cross-head, means therein adapted to permit the longitudinal movement of said piston rods without any leakage of gas from the combustion chamber adjacent thereto, and means for providing a circulation of the liquid lubricating medium of the motor through said piston rods and piston.
3. In a motor of the kind described a

cylinder, two combustion chambers in said cylinder separated one from the other by a hollow double acting piston, two hollow piston rods connected to the double acting piston and formed to correspond with and fit against the sides of the interior of the cylinder, a stationary cross-head, and means therein adapted to permit the longitudinal movement of said piston rods without any leakage of gas from the combustion chamber adjacent thereto, said means comprising a contracting ring carried by the cylinder and adapted to bear against the outer surface of each of said piston rods, an expanding ring carried by the cross-head and adapted to bear against the inner surface of each of said piston rods, spring wedges adapted to bear against each of the sides of each of said piston rods, and means for providing a circulation of the liquid lubricating medium of the motor through said piston rods and piston.

4. In a motor of the kind described, a cylinder having a cross-head forming in said cylinder an explosion chamber and pump chamber, a hollow piston traversing said explosion chamber, a pump piston traversing said pump chamber, means for supplying liquid lubricating medium to the pump chamber above the pump piston, and means for circulating the lubricant above the pump piston through the hollow piston.

5. In a motor of the kind described, a cylinder having a cross-head forming in said cylinder an explosion chamber and a pump chamber, a hollow piston traversing said explosion chamber, a pump piston traversing said pump chamber, a piston rod connecting said pistons, means for supplying liquid lubricating medium to the pump chamber above the piston, and means for 105 circulating the lubricating medium above the pump piston through said piston rod and hollow piston.

6. In a motor of the kind described, a cylinder having a cross head forming in said cylinder an explosion chamber and a pump chamber, a hollow piston traversing said explosion chamber, a pump piston traversing said pump chamber, piston rods connecting said pistons and lying in contact with the wall of said cylinder, means for supplying liquid lubricating medium to said pump chamber above the pump piston, and means whereby the traverse of the pump piston circulates said lubricating medium 120 through said piston rods and hollow piston.

7. In a motor of the kind described, a cylinder having a cross head forming in said cylinder an explosion chamber and a pump chamber, a hollow piston traversing said explosion chamber, a pump piston traversing said pump chamber, piston rods connecting said pistons and lying in contact

with the wall of said cylinder, having openings in communication with the opening in said hollow piston and opening out above and adjacent to said pump piston, means 5 for supplying liquid lubricating medium to said pump chamber above the pump piston, said lubricating medium being circulated

through said piston rods and hollow piston, and means for cooling the wall of said cylinder.

STEPHEN JENCICK.
